UNITED STATES PATENT OFFICE.

LEWIS LEONARD, OF COUNCIL BLUFFS, IOWA.

SAFETY RAILWAY GATE.

Application filed March 24, 1924. Serial No. 701,327.

This invention relates to a safety gate for railway crossings, and has for its object to provide arms adapted to be coincidentally swung as signal warnings to prevent a movement of vehicles or pedestrians across the tracks of railways, and thereby prevent injuries from moving trains, the parts provided for these purposes to be few and simple, so that the construction will be economical, and will be durable and practical in use.

With the foregoing objects in view the invention presents a novel and useful construction, combination and arrangement of parts as described herein and claimed, and as illustrated in the accompanying drawing, wherein,

Fig. 1 is a side view of the device. Fig. 2 is a plan view of the same. Figs. 3 and 4 are side views showing a housing for certain mechanism employed for moving the signal arms, the arms shown in Fig. 3 being in horizontal positions, and the arms shown in Fig. 4 being disposed vertically.

Referring now to the drawing for a more particular description, the invention is shown and described in connection with a housing 5 disposed between a road bed or highway 6 and a sidewalk 7 extending across a railway track 8.

Numeral 9 indicates a shaft having bearings in the sides of the housing. At 10 is indicated a signal arm having side strips 11 disposed outwardly of the sides of the housing and rigidly secured to the shaft 9, said strips 11 preferably being constructed of light-weight material and provided at one of their ends with counterbalances 12 having flanges 13 and secured to the side strips 11 by any suitable means.

Any suitable means may be provided for operating the shaft 9 for reciprocation of the arm 10 in an arc, approximately, of 90

degrees to the upright position shown in Fig. 4 as a signal and permitting travel on the highway 6 and sidewalk 7, or for moving said arm downwardly to, approximately, a horizontal position as shown in Fig. 3, as a signal to prevent travel across the railway tracks.

Numerals 14 indicate a pair of signal arms 50 which may extend across the sidewalk 7 to prevent a passage thereon of pedestrians, and which may be moved upwardly to permit such passage, said arms being mounted on a shaft 15 in suitable bearings. Upon 55 each arm or strip 14 is pivotally mounted a link 16, said pivotal mounting being indicated at 17 at or near one of the ends of said link, the opposite end being mounted pivotally, as indicated at 18 on a strip 11 of the signal arm 10, and it will be seen that when the signal arm 10 swings downwardly the arms or strips 14 will also swing downwardly, and when the arm 10 swings upwardly the arms or strips 14 will swing upwardly, the pivotal mounting 18 for each link 16 being upon that part of a side-strip 11 between its counterbalance and the shaft 9.

I claim as my invention:

A safety gate for railway crossings, comprising a housing, a shaft journaled therein, a road crossing gate composed of side strips each provided with a counterbalance and secured upon opposite ends of the shaft, a side walk gate composed of a pair of side strips journaled on the sides of the housing, and a link connecting each of the last named strips with a side strip of the first named gate between the counterbalance and the shaft.

In testimony whereof, I have affixed my signature.

LEWIS LEONARD.
